UNITED STATES PATENT OFFICE

2,229,443

PLUG FUSE

John C. Dallam, Bridgeport, Conn., assignor to
General Electric Company, a corporation of
New York

Application November 30, 1938, Serial No. 243,133

6 Claims. (Cl. 200—119)

The present invention relates to plug fuses, and more particularly to non-tamperable plug fuses such as are used to protect individual electric circuits, for example, in house wiring systems.

5 In connection with plug fuses it is known that in instances where a fuse blows and a spare fuse is not available the circuit may be shorted by removing the plug fuse, placing a piece of tin foil, a coin or other conducting member in the 10 fuse socket and then replacing the plug fuse. This practice of shorting around an ordinary plug fuse when the fuse burns out is dangerous inasmuch as it eliminates the fuse protection for the 15 circuit and permits the line to be overloaded. Overloading a line may result in serious trouble and may be the cause of a fire.

One object of the present invention is to provide an improved plug fuse structure comprising a plug fuse and adapter for use with a standard 20 fuse socket and which makes it very difficult to short circuit a burned-out fuse plug; so difficult, that an ordinary user would find it impossible to do so.

25 A further object of the invention is to provide an improved plug fuse which, while it is intended for use in a plug fuse socket having an adapter therein, may be used also in a standard socket not provided with an adapter. This is an important consideration since it means that the single plug fuse structure is adapted for universal use thus making it unnecessary for the sale outlets to stock more than one kind of a plug fuse.

30 Another object of the invention is to so construct the adapter that it may be seated within the plug socket by means of the plug fuse, thereby obviating the need of special tools to insert the adapter.

35 A further object of the invention is to provide an improved plug fuse structure and adapter of the non-tamperable type which are simple in structure and which may be manufactured at low cost.

40 In the accompanying drawing Fig. 1 is a sectional view through a fuse socket showing the plug fuse and adapter seated in position; Fig. 2 is a view similar to the showing of Fig. 1 but, in addition, showing the plug fuse and adapter in cross-section; Fig. 3 is a top plan view of the 45 adapter taken along the line 3—3 of Fig. 1; Fig. 50 4 is a plan view of the bottom of the plug fuse taken substantially along the line 4—4 of Fig. 2; Fig. 5 is a detailed view showing the manner in which the plug fuse and adapter are interengaged for seating the adapter in the fuse socket;

Fig. 6 is an elevational view of the plug fuse showing the manner in which it may be used in a fuse socket without the adapter, and Fig. 7 is an elevational view of the adapter.

Referring to the drawing, the non-tamperable 5 fuse structure comprises a plug fuse 10 and an adapter 11.

As shown by Figs. 1 and 2, the plug fuse and adapter are mounted together within a fuse receptacle 12, such as a fuse box, which is customarily installed in house wiring systems. The fuse receptacle is provided with an insulating housing 13 such as porcelain, a screw shell 14 forming one contact of the receptacle, and a center screw 15 forming the other contact. An insulating disk 16 insulates the shell 14 from the screw 15. The head of the screw bears against a washer 17 resting upon the disk 16, which in turn, rests upon a second washer 18 seated on the bottom of the screw shell. In this manner 20 the screw 15 serves to hold the assembled shell and insulating disk in position upon the housing. In use, one side of the circuit is connected to the center contact screw 15 and the other side 25 is connected to the screw shell 14.

Viewing Figs. 2, 4 and 6 it will be seen that the plug fuse 10 comprises a bushing 20 and a skirt 21, both formed of insulating material, such as a phenolic condensation product, or the like, and which are held together by a screw-threaded 30 metal shell 22. The shell engages screw threads 23 formed on the skirt 21 and is provided with an inturned flange 24 which engages the bushing and draws it into engagement with the skirt as the shell 22 is threaded down upon the latter. A contact pin 25 extends from the bottom of the bushing. The contact pin is formed with a flange 26 resting in a recess in the bottom of the bushing and the other end of the contact pin is peened over projections extending from 40 the upper face of the bushing, as shown at 27, to secure the contact pin to the bushing. A fusible element 28 is secured to the end of the contact pin by solder 29. In order to provide 45 a blow chamber for the fuse, the skirt 21 is formed with a recess 30 which merges with a sight opening 31. The sight opening is provided with a window pane 32 of mica, or the like, which seals the blow chamber from the sight opening 50 and which, at the same time, permits the condition of the fuse to be viewed. The window pane 32 is supported upon an insulating sleeve 33 of fiber, or the like, which rests on the bushing 20. In addition to supporting the mica pane 55

32, the sleeve protects the walls of the recess from damage upon blowing of the fuse. In order to contact the outer screw shell 22, the fuse link 28 extends through a slot 34 in the sleeve, then 5 through the space between the sleeve and the wall of the recess and thence through a slot 35 in the wall of the skirt to a groove 36 formed in the outer wall of the skirt where it is connected to the shell by means of a soldered joint 38. 10 The joint 38 being located in the groove 36 prevents the shell 22 from becoming unscrewed from the skirt 21.

The bushing 20, forming the base of the fuse 15 10, is provided with an extending annular wall or flange 40 so disposed that it forms a central cylindrical recess 41 and an outer concentric circular groove 42. The flange 40 is formed with a plurality of circumferentially disposed slots 43 while the groove 42 is formed with several cam surfaces 44. The slots 43 and the cams 44 cooperate with the adapter 11 in a manner to be described later.

The adapter is an annular disk formed of insulating material, such as a phenolic condensation product, or the like, and is provided with screw threads 45 which are adapted to seat it within the screw shell 14 of the fuse receptacle. One end of the adapter is provided with a plurality of concentric grooves, the inner groove 47 25 being deeper than the outer groove 46. Between grooves 46 and 47 is an annular wall 48 and in the upper edge of the wall are serrations 49 forming sharp-edged teeth. A central opening 50 is adapted to receive the contact pin 25.

30 In the use of the non-tamperable fuse structure, the plug fuse 10 and adapter 11 are mounted together within the fuse receptacle, as shown in Figs. 1 and 2. To insert the adapter within the receptacle it is united with the plug fuse by inserting the contact pin 25 in the adapter opening 50. In this position, the cams 44 in the groove 42 engage the serrations or teeth 49 formed in the wall 48, as shown most clearly in Fig. 5, while the flange 40 is disposed within the groove 47. It 35 will be apparent that the adapter and fuse may now be rotated together by grasping the top of the fuse to seat them within the receptacle shell. The contact pin is of sufficient length to project slightly below the edge of the adapter, when the latter is in seated position, to engage the contact 40 15 while the outer fuse shell 22 engages the receptacle shell. In this manner the fuse is placed in the circuit. The plug fuse may be readily unscrewed for replacement or change leaving the 45 adapter seated permanently within the fuse receptacle. When this is done the cam surfaces 44 simply slide over the saw teeth 49 thereby disengaging the plug fuse from the adapter. The 50 adapter cannot be removed from the receptacle 60 because the teeth on the adapter grip the plug fuse cams only upon rotation of the cams in one direction, i. e. when the fuse is being screwed into the receptacle, and the adapter is frictionally retained in position by engaging the wall of the 65 screw shell.

70 With an adapter in the socket an ordinary plug fuse cannot be used. A fuse is required having a contact pin 25 of sufficient length to extend through the opening 50 into engagement with the center contact 15. When a fuse burns out, the fuse can be readily unscrewed, in the manner indicated, but can be replaced only with a plug fuse of the same type. For all practical purposes the adapter and fuse make up a tamper-proof construction. In order to short circuit a fuse

receptacle having an adapter 11 therein, it will be necessary to provide a connection from the center contact 15 through opening 50 in the adapter to screw shell 14. This would be difficult. It cannot be done with a coin. If tinfoil or a 5 piece of wire were passed through opening 50 into engagement with center contact 15 and then extended across the adapter into engagement with screw shell 14, upon attempting to replace the plug fuse 10, the flanges 40 and 48 entering 10 the grooves 41 and 42, respectively, would tend to sever the foil or wire, or else carry it from engagement with center contact 15 and receptacle shell 14. Under these circumstances, the serrations or teeth 49 cooperate with the slots 43 15 in the flange 40 in tearing the foil or else in catching the foil or wire and twisting it circumferentially.

20 By the construction described it will be seen that an effective tamper-proof plug fuse structure is to be had and one which may be employed with any standard plug fuse receptacle. Not only do the serrations or teeth 49 cooperate with the slotted flange 40 in tearing or disarranging any shorting strip, but the teeth also cooperate with 25 cams 44 on the plug fuse to provide a simple and effective means for seating the adapter within the receptacle. No special tool is needed to seat the adapter in position.

30 The plug fuse 10, shown by Fig. 6, may be used with or without the adapter. When the tamper-proof construction is not employed by omitting the adapter 11, the fuse 10 may be inserted within a receptacle and employed as a conventional plug fuse. In such cases the contact pin 25 engages 35 the center contact 15 and the fuse shell 22 engages the receptacle shell 14. Thus, the plug fuse, constructed in accordance with the invention, may be used as an ordinary fuse or may be joined with the adapter to provide a tamper-proof fuse. By employing the same plug fuse in both cases, only one construction need be built by the manufacturer and stocked by the sales outlet and the adapter may be installed separately as occasion demands.

45 What I claim as new and desire to secure by Letters Patent of the United States is:

1. In a tamper-proof fuse construction for use with a fuse receptacle, an adapter for said fuse for seating within the receptacle, said adapter having an opening therein and being provided with a wall having serrations therein, a plug fuse having a center contact passing through said opening to engage a contact in said receptacle, and cam means on said fuse engaging said serrations to seat said adapter in said receptacle as the fuse is threaded therein.

2. In a tamper-proof fuse construction for use with a plug receptacle having a threaded contact shell, an adapter for seating within said shell, 60 said adapter being provided with a wall having serrations therein and a plug fuse having a threaded contact shell for engaging said receptacle shell, and cam means on said fuse engaging said serrations to seat said adapter in the 65 receptacle shell as the plug fuse is threaded into said shell, said cam means disengaging said serrations upon unscrewing of said plug fuse from said receptacle whereby said adapter is left in position.

3. In combination, a plug fuse having an annular groove formed in the base thereof, cam surfaces formed in the bottom of said groove, an adapter having an annular wall provided with serrations therein, said cam surfaces engaging 70 75

said serrations whereby said fuse and adapter may be positioned as a unit within a fuse receptacle.

4. In a tamper-proof fuse construction for use with a fuse receptacle having a threaded shell, the combination of a plug fuse having a threaded contact shell for engaging said receptacle shell, said fuse having an annular groove in the bottom wall thereof, one-way cam surfaces disposed in the bottom of said groove, an adapter comprising an annular disk of insulating material having screw threads thereon for insertion in said receptacle shell, an annular wall formed on said adapter and provided with serrations therein for engaging said cam surfaces as said fuse and adapter are joined together with said wall resting in said groove, said cams and serrations engaging one another to thread said adapter into the receptacle shell as said fuse is threaded therein to position said adapter in the bottom of said receptacle, and said cams and serrations disengaging upon unthreading of said fuse from said receptacle to leave said adapter seated in position.
5. In a tamper-proof fuse construction for use with a fuse receptacle having a threaded contact shell and a center contact, the combination of a plug fuse having a threaded contact shell and a center contact pin, an annular flange having slots
- therein projecting from the bottom of said fuse and surrounding said pin, said fuse having an annular groove adjacent said flange, cam means formed in said groove, an adapter comprising a threaded annular disk of insulating material having an opening therethrough, said adapter having a wall provided with teeth, said adapter and fuse coacting as a unit for threading within said receptacle with said cam means engaging said teeth and said contact pin extending through said opening into engagement with said contact, said cam means and teeth preventing relative rotation between said adapter and fuse whereby said adapter is seated within said receptacle upon threading of said fuse and being releasable upon unscrewing of said fuse from said receptacle to leave said adapter seated in position.
6. In a tamper-proof fuse construction for use with a plug receptacle having a threaded contact shell, an adapter for seating within said shell, said adapter being provided with a wall having serrations therein, a plug fuse having a threaded contact shell for engaging said receptacle shell and projecting means on said fuse cooperating with said serrations to seat said adapter in the receptacle shell as the plug fuse is threaded into the shell.

JOHN C. DALLAM.
